CARPET.

No. 18,130.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,130, dated March 6, 1888.

Application filed January 26, 1888. Serial No. 262,053. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

15 The accompanying photograph is a face view of a carpet showing my new design.

My design consists of a number of rose-shaped flower forms, the leaves of which are more or less open. These flowers are disposed

over the surface of the carpet at irregular intervals, and are connected by an underlying 20 stem-work. Around or near each flower form are large leaves, generally arranged in groups of three. There are several groups, also, of smaller triangular-shaped flower forms. The intervening spaces are intersected by short 25 branch stems or twigs bearing small leaves and star-shaped flowers.

What I claim as new, and desire to secure by Letters Patent, is—

30 The design for carpets, consisting of the design substantially as shown.

JAS. L. FOLSOM.
